(57) **CLAIM**

The ornamental design for an electrode cover for a plasma processing apparatus, as shown and described.

DESCRIPTION

FIG. 1 is a front, top and right side enlarged perspective view of an electrode cover for a plasma processing apparatus showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a cross-sectional view taken along line 8-8 of FIG.

6; and,

FIG. 9 is an enlarged portion view taken along line 9-9 of FIG. 8.

1 Claim, 5 Drawing Sheets
